DESIGN FOR A MINIATURE AIRPLANE ENGINE

Irwin G. Ohlsson, Los Angeles, and Henry T. Rice,
San Gabriel, Calif.

Application July 11, 1938, Serial No. 78,384

Term of patent 3½ years

To all whom it may concern:

Be it known that we, Irwin G. Ohlsson and Henry T. Rice, citizens of the United States and residing at Los Angeles, in the county of Los Angeles and State of California, and San Gabriel, in the county of Los Angeles and State of California, have invented a new, original, and ornamental Design for a Miniature Airplane Engine, of which the following is a specification, reference being had to the accompanying drawing forming a part thereof.

In the accompanying drawing, Fig. 1 is a front elevation of our new miniature airplane engine; Fig. 2 is a side elevation of the engine; and Fig. 3 is a top plan view of the engine.

We claim:

The ornamental design for a miniature airplane engine, as shown.
